CLAIM

The ornamental design for a phased-array radar, as shown and described.

DESCRIPTION

FIG. 1 is a perspective view of a phased-array radar showing the new design.

FIG. 2 is a front view of the phased-array radar of FIG. 1.

FIG. 3 is a rear view of the phased-array radar of FIG. 1.

FIG. 4 is a side view of the phased-array radar of FIG. 1.

FIG. 5 is an opposite side view of the phased-array radar of FIG. 1.

FIG. 6 is a top view of the phased-array radar of FIG. 1; and, FIG. 7 is a bottom view of the phased-array radar of FIG. 1. The broken lines show portions of the phased-array radar that form no part of the claimed design.
